his Attorney.

UNITED STATES PATENT OFFICE.

ALEXANDER S. MEEK, OF WASHINGTON, IOWA, ASSIGNOR OF ONE-HALF TO SMITH P. WHITE,
OF CHICAGO HEIGHTS, ILLINOIS.

WINDOW-SASH VENTILATOR.

No. 910,934.

Specification of Letters Patent.

Patented Jan. 26, 1909.

Application filed August 29, 1908. Serial No. 450,846.

To all whom it may concern:

Be it known that I, ALEXANDER S. MEEK, a citizen of the United States, residing at Washington, in the county of Washington and State of Iowa, have invented certain new and useful Improvements in Window-Sash Ventilators, of which the following is a specification, reference being had therein to the accompanying drawing.

10 This invention relates to ventilators, and more particularly to window sash ventilators, and it has for its object the provision of means for facilitating the operation of the ventilator.

15 Another object of this invention is the production of a ventilator which is simple in construction, and consists of a minimum number of parts.

20 Still another object of this invention is the production of a ventilator which constitutes a hinged gate, and which can be automatically locked in an open or closed position.

25 With these and other objects in view, this invention consists of certain novel constructions, combinations, and arrangements of parts, as will be hereinafter fully described and claimed.

30 In the drawings: Figure 1 is a plan view of the ventilator in connection with a window sash. Fig. 2 is a sectional view taken on line 2—2, Fig. 1, looking in the direction of the arrow. Fig. 3 is a detail perspective of the angle member which connects with the door or gate. Fig. 4 is an enlarged view of the 35 locking mechanism for the vertical rod.

Referring to the drawings by numerals, 1 designates a sash which is provided with a front opening 2, which opening 2 acts as a ventilating means. The opening 2 is provided with an outwardly-extending member 3, to the outer end of which is hinged a gate or door 4. At the junction of the member 3 and the gate 4, the edges of said member 3 and gate 4 are beveled, as at 4^a, so as to form 40 a tight joint when the gate 4 is in a closed position. The top of the frame is provided with a notched portion 4^b, in which is adapted to fit the upper edge of the hinged gate 4, thereby forming a tight joint between the 45 upper edge of the frame and the hinged gate or door 4.

Secured to the gate 4 is an angle member 5, which is provided with an inwardly-extending portion 5^a. The lower end of said inwardly-extending portion is bifurcated, as at

6, and an aperture 7 is formed near the end of said inwardly-extending portion.

An angle bracket 8 is secured to the sash 1, and the outwardly-extending flanged portion is provided with an aperture 9. A vertical 60 rod 10 passes through said aperture, and said rod is bent outwardly near its upper end and terminates into an eye 11, and said eye 11 passes through the aperture 7 and the bifurcated end 6 of the angle member 5. By being so secured to the lower end of said angle member 5, it will be seen that the rod 10 will be held in a set position against rotation. The inner side of the rod 10 is provided with teeth 12, which teeth are adapted to engage 65 the side of the aperture 9 of the angle bracket 8. Secured to the sash 1 is a flat spring 13, and said flat spring is provided with an outwardly flanged portion 14. The rod 10 passes through this aperture and the purpose 70 of the spring 13 is to normally hold the teeth 12 of the rod 10 in engagement with the edge 75 of the aperture 9 of the bracket 8.

It can be readily seen that by slightly pulling the rod 10 outwardly the spring 13 will 80 yield and disengage the teeth 12 upon the rod 10 from the edge of the aperture 9 of the bracket 8 and allow the rod to freely move up or down, so as to open or close the gate or door 4. Therefore, it will be seen that I have 85 provided a device by which a ventilating door can be opened or shut, and be automatically locked in such a position.

What I claim is:

1. In a device of the class described, the 90 combination with a window sash, said sash provided with an opening, of a gate or door hinged to the bottom of said opening, an angle member secured to said door, one portion of said angle member projecting below 95 said door, a vertical rod connected to the lower end of said angle member, and means positioned upon the sash and engaging said vertical rod for locking said hinged door or gate in an open or closed position. 100

2. In a device of the class described, the combination with a window sash, of an apertured angle bracket constituting a guide, a rod passing through said aperture in said angle bracket, said rod provided, on one side, 105 with teeth, said teeth adapted to engage the sides of the aperture in said angle bracket, a flat spring secured to said sash and terminating at its lower end into an outwardly-extending portion, said outwardly-extending 110

portion provided with an aperture, said rod passing through said aperture, and said flat spring constituting means for normally holding said teeth upon said rod in engagement with the sides of said aperture in said angle bracket.

3. In a device of the class described, the combination with a window ventilator, of an operating rod, an angle-bracket, said angle bracket provided with an aperture, teeth formed upon said rod, and means passing around said rod and secured to a support for normally holding said teeth in engagement with the side of said aperture.

10 4. In a device of the character described, the combination with a window sash, said sash provided with an opening near one end, an outwardly extending portion secured at its inner end to one side of said opening, and 20 said portion provided with an outer beveled edge, a swinging door provided with a lower beveled edge, means interposed between the beveled edges of the hinged gate or door and the outwardly extending portion, for hinging 25 the same together so as to form a tight joint, and means secured to said door for manually operating the same and locking said door in an open or closed position.

5. In a device of the character described, 30 the combination with a window frame, a slideable sash positioned in said frame, said frame provided with a notch formed along the inner edge of the top thereof, said sash provided with an opening near one end, and

an outwardly extending portion secured at 35 its inner end to one side of said opening, a door hinged to the outer edge of said outwardly extending portion, the upper edge of said hinged door adapted to fit snugly in said groove or notch formed in the edge of said 40 frame, and means secured to said door for manually operating the same and locking said door in an open or closed position.

6. In a device of the character described, the combination with a window sash provided with an opening near one end, an outwardly extending portion secured at its inner end to the bottom of said opening, a door hinged to the outer edge of said outwardly 45 extending portion, an angle member secured 50 at one end to said hinged door by means of screws passing through apertures formed therein, said angle member provided with a downwardly extending portion, said downwardly extending portion provided with a 55 lower bifurcated end and a transverse aperture formed directly in the rear of said bifurcation, and means passing through said aperture and having one end positioned in said bifurcated end for actuating said angle member, for opening or closing said door.

In testimony whereof I hereunto affix my signature in presence of two witnesses.

ALEXANDER S. MEEK.
